UNITED STATES PATENT OFFICE

GEORGE J. ROBERTSON, OF MAHTOMEDI, MINNESOTA

DESIGN FOR A COIN CONTROLLED DISPENSING DEVICE

Application filed November 13, 1931. Serial No. 41,713. Term of patent 3½ years.

To all whom it may concern:

Be it known that I, GEORGE J. ROBERTSON, a citizen of the United States, residing at Mahtomedi, in the county of Washington and State of Minnesota, have invented a new, original, and ornamental Design for Coin Controlled Dispensing Devices, of which the following is a specification, reference being had to the accompanying drawings forming part thereof.

Fig. 1 is a top view, Fig. 2 is a front view and Fig. 3 a side elevation of a coin-controlled dispensing device, showing my new design.

I claim:

The ornamental design for a coin-controlled dispensing device, as shown.

GEORGE J. ROBERTSON.
